UNITED STATES PATENT OFFICE.

FITZHUGH TOWNSEND, OF NEW YORK, N. Y.; JOHN J. TOWNSEND, ADMINISTRATOR OF
SAID FITZHUGH TOWNSEND, DECEASED, ASSIGNOR TO GENERAL RAILWAY SIGNAL
COMPANY, A CORPORATION OF NEW YORK.

SYSTEM OF AUTOMATIC BLOCK-SIGNALING FOR ELECTRIC RAILWAYS.

1,178,192.

Specification of Letters Patent.

Patented Apr. 4, 1916.

Application filed March 5, 1906. Serial No. 304,373.

To all whom it may concern:

Be it known that I, FITZHUGH TOWNSEND, a citizen of the United States, residing at New York city, county, and State of New York, have invented a System of Automatic Block-Signaling for Electric Railways, of which the following is a specification.

My invention relates to improvements in block signaling systems of the types used on electric railways in which one or both of the traffic rails are employed as a return for the power current. In a system of this character it is desirable to tie together electrically, or cross-bond, the rails of the several track-ways, in order that the current from a motor vehicle may readily distribute itself among all of the conducting tracks. In carrying out this idea, it is also desirable that a break or electrical interruption in any track rail shall cause the signal to go to the danger position, so as to prevent a train from becoming derailed.

It is the purpose of my invention to accomplish both of the results described; namely, cross-bonding between tracks, and protection against a broken rail.

The accompanying diagrams illustrate modifications of my invention. In all of them the type of block signaling system and electric railway shown is a signaling system using reactance bonds and a direct power current, both rails forming the return of such power current.

In Figure 1, a four track railway is shown, the protective and signaling devices being shown for one trackway, the understanding being that in the case of the three remaining trackways, these devices would be reproduced. Cross-bonding is secured by electrically connecting one rail of each trackway with all the other corresponding rails. Protection against a broken rail is secured by means of protective reactances and traction relays normally actuated by the drop across such reactances so as to maintain the signaling circuit normally closed, but to allow it to be opened in the case of a broken rail. An alternating current of a different characteristic from either the power current or the block signaling current is transmitted through all of the traffic rails in parallel with each other in order normally to energize the protective devices, closing the contact of all the protective re-

lays in the absence of a broken rail. Fig. 2, shows a modification in which resistances similar to an ammeter shunt are inserted in the trackway. Across each resistance is connected a protective relay, adapted to open when there is a break in a traffic rail. A direct current is continuously sent through the trackway for the purpose of energizing the protective devices by producing a drop, or difference of potential, across the resistances just mentioned. Fig. 3, shows a modification in which a selective relay, responsive only to the signaling current, normally actuated by the difference of potential or drop across the protective reactance is employed. The protective devices are operated by current from the track transformer which normally energizes the block section in the operation of systems of this type. The same is true of Fig. 4. Only one trackway is shown. One rail of this track is electrically connected to a conductor, which diagrammatically indicates the rest of the track return or such part of it as the cross-bonded track rail would properly be connected to. Fig. 4, shows a modification in which a selective relay, responsive only to the signaling current, is employed to indicate a broken rail. The relay is connected across the protective reactance which is inserted directly in the cross-bond. Fig. 5 shows a modification of the method shown in Figs. 1, 2 and 3, for inter-connecting the traffic rails of a four track railway. In this diagram the signal controlling devices, together with the signals, are omitted.

Considering my invention in detail, the following features are common to Figs. 1-4: The power generator A is connected to the trolley or feeder conductor 1, and to the traffic rails 2 and 3 through the conductor 4, and a reactance bond B. The motor vehicle C is operated from conductor 1, the signaling generator D is connected to the conductors 5 and 6 and through transformers E and conductors 7 and 8 supply signaling current to the rails 2 and 3 of each block section. This signaling current maintains a difference of potential between the traffic rails 2 and 3 and controls the position of the signal F by means of relay devices. These signals are normally maintained in the clear position by the current from battery G, which current flows

through the local signaling line 9, energizing the solenoid H, and holding the signal in the clear position by attracting the counter-weight core J. The cross-bonding conductors 10 and 11, connect the traffic rails 2 and 3 to other portions of the track return. An accidental break in the traffic rail is denoted by O, and X, Y, Z represent three block sections. In Figs. 1 and 2, the traffic rails 2 are connected by cross conductor 10 and the traffic rails 3 by a cross conductor 11 and bonds B. Interposed between cross conductor 11 and rail 2 are reactances 12 on open core 13, (Fig. 1). Reactance coils 12, wound upon cores 13, are connected to the adjacent ends of the sections of traffic rail 2, an intermediate point between said coils being also connected to an intermediate point between the adjacent bonds B. 14 is a relay, which I term the break relay, having one terminal of its coil connected to one terminal of the coil 12, and its other terminal connected to the terminal of the secondary coil 15, which coil 15 has its other terminal tapped on to some point of the coil 12. The armature 16 of the relay 14, is connected to a contact 17, in the path of movement of the arm 18 of the signal relay 19. It will be observed that under normal conditions, as indicated in blocks Y and Z, the path of the local signaling current from battery G includes the armatures 16 of the two relays 14, the arm 18 of the relay 19 and the contact 17. The signal relay shown in Figs. 1 and 2 is of the polyphase type. One coil, 20, of the stator of this relay is connected across the traffic rails 2, 3, and is normally energized by the track circuit current which is supplied to the block section from the track transformer E the terminal 7, being connected to rail 2, through conductor 11 and coils 12. The other coil, 21, of the relay 19, is energized from conductors 5 and 6 and by means of phase control provision is made for the adjustment of phase displacement between the currents carried by coils 20 and 21. K, Fig. 1 and L, Fig. 2, are respectively an alternating and a direct current generator, one terminal of which is connected to the conductor 23, which runs to the end of the line where it is connected to the track return. The other terminal of the generator K is connected by means of conductor 24, conductor 4 and bonds B to the rails 2, 3, at the generator end of the line.

The operation of the embodiment of my system shown in Fig. 1 is as follows: The generator K should preferably be of different frequency from that of the signaling generator D. There are, therefore, two signaling currents of different frequencies and different electrical paths. The generator D supplies the track circuit signaling current, which produces a difference of potential between the traffic rails of each block, flowing up one rail and down the other. The generator K, on the other hand, sends a current through the entire track return, passing from one block to the next, this current flowing through all of the traffic rails in the same direction. Its value in any traffic rail, is, therefore, the same; independently of the position of the motor vehicles, and this current will only change in value in any portion of the traffic rails provided there is an electrical break or a discontinuity in any of such traffic rails. In other words, the generator K supplies current for indicating a broken rail, while the track circuit current from generator D is used to indicate the presence or absence of the motor vehicles in the several block sections. The track relays 19 are only responsive to the difference of potential between the traffic rails due to the signaling current, while the protective relays 14 are responsive to the current supplied by the generator K, independently of the difference of potential between the traffic rails. In an electric railway there are frequently times when in some portion of the track return there is an absence of propulsion current. It is under these conditions that the current from generator K is necessary to energize the relays 14 so as not to open the signaling line 9 and give a wrong danger signal. It will be seen that owing to the method of connections of the relay 14, a portion (which may be any portion) of the drop due to the propulsion current flowing through the coil 12, will be developed across said relay, thus energizing it provided the value of the propulsion current required for this purpose has been reached. The point at which the secondary 15 is connected to the winding 12 should be chosen in such a way that when the propulsion current begins to saturate the core 13 and consequently obliterates the reactance of the coil 12, the ohmic drop due to the propulsion current shall be sufficient to energize the relay 14. It will be understood, of course, that the relay 14 is of a type which can be energized by direct or alternating currents, separately or together. The protective relays 14 indicate the condition of the rail 2. If a break were to occur in the rail 3, however, in any block section, this would be indicated by the opening of the contact 17 of the track relay 19.

In Fig. 2 a direct current generator L takes the place of alternating generator K in Fig. 1. Resistance 33 is substituted for reactance 12. In other respects the figures are the same. It will be seen that the difference between Fig. 1 and Fig. 2 is that in Fig. 2 the protective devices are energized by the drop due to a direct current passing through resistance 33. This, D. C. drop is sufficient to energize the relay 14 in the ab-

70 75 80 85 90 95 100 105 110 115 120 125 130

sence of a break in the traffic rail 2. Owing to the lower ohmic resistance of the track return the power supplied by the generator L need not be very great in order to produce the requisite number of D. C. amperes.

In Fig. 3 only the power generator A and the signaling generator D are present. The protective devices are normally energized by the track circuit current from the generator D. A selective break relay 34, is employed to indicate a discontinuity in the rail 2. This relay is of any well known selective type, having one coil 25 connected across a reactance 26, the other coil 27 of the relay being supplied with current from the generator D through the transformer P. This relay is responsive only to the signaling current. The coil 26 should be made of a type now well known in which the reactance is unaffected by the passage of the full power current through the coil. The signaling relay employed here may be, of course, of any type, but it is shown as a selective relay 30, of a similar type to the break relay 34. The cross-bonds 10 connect the traffic rail 2 to the conductor 28, Figs. 3 and 4. This conductor 28 may be other traffic rails similar to rail 2, or indeed a ground connection, or any auxiliary return conductor or conductors.

In Fig. 4, the protective reactances 26 are inserted directly in the path of the cross-bonds 10. The relay 34 closes the circuit of the battery G by means of a back contact 29. This is because when all of the traffic rails are perfect, they will each have approximately the same conductivity, so that the cross bonds 10 will carry little or no signaling current. The relay 34 will, therefore, be deenergized normally so as to avoid breaking the circuit of the local signaling line 9. When a break in the traffic rail 2 occurs, as at the point O, however, the signaling current will flow through the cross-bonds 10, producing a drop in potential across the reactance 26, thereby energizing the relay 34 and opening the contact 29, so as to send the signal F to the danger position.

In Fig. 5, the diagram illustrates an arrangement of cross bonding which may be employed in an electric railway of many parallel tracks where the signals in the various tracks do not come opposite each other. The cross bonds 10 and the reactance bonds B perform the same functions as in the other figures with regard to the rails 2 and 3. The signaling apparatus and the propulsion apparatus are omitted from the diagram.

I wish it understood that the arrangement of reactance bonds shown has nothing to do with the means for indicating a break in a traffic rail, and I do not limit myself

to the particular arrangement of cross bonds shown in these diagrams. Furthermore, a protective device may be arranged in connection with each of the traffic rails instead of only one, if desired, and various other 70 modifications may be made.

I have described and shown my invention as applicable to an electric signaling system where the propulsion current for operating motor vehicles is a direct current. Manifestly, it may be employed in a system where the propulsion current is an alternating current and without requiring any changes other than will be within the comprehension of signaling engineers. Thus I 80 may vary the means by which the current, which normally actuates the break relays, is fed to the trackway. The character of said relays, as also the means by reason of which two signaling currents are differentiated between the break and signaling relays.

The drawings in this application, being simply diagrams, are merely intended to show several arrangements by which my 90 inventions may be carried into effect and are not intended to describe all of the arrangements which I have conceived for the purpose.

Having thus described my invention, I 95 claim:

1. In a signaling system of the type described, means for impressing signaling current upon the rails, means for indicating a break in the continuity of the rails, said means comprising a current differing in character from the signaling current impressed upon the rails, a relay device normally actuated by said current and signaling devices under the control of said relay devices.

2. In a signaling system of the type described, the combination of a source of propulsion current, a source of signaling current, a second source of signaling current, said signal currents having different characteristics, together with a translating device subject to the separate control of both said signaling currents, and a signal controlled by said translating device.

3. In a signaling system, a sectional trackway which serves as a return for the propulsion current, a signaling current impressed upon each section of the said trackway and adapted to create a difference of potential between the rails thereof, a second signaling current impressed upon the whole trackway and adapted to produce a difference of potential between the ends of the trackway, and signaling devices under the control of both currents.

4. In a signaling system of the type described, a trackway, block sections into which the trackway is divided, means for generating current for operating motor

vehicles on the railway, means for generating a current differing in character to set up a difference of potential between the rails of the respective block sections of said trackway and means for creating a difference of potential between the ends of the trackway, relays under the influence of said signaling current, relays controlled by the said other difference of potential, signals controlled by said relays, together with means for preventing the propulsion current from influencing said relays.

5. In a signaling system of the type described, the combination of means for connecting parallel lines of trackway to act as return paths for the propulsion current, said trackway divided into block sections, means to indicate the occupancy or non-occupancy of a block section and translating devices responsive to a break in such rails.

6. In a signaling system, the combination of a trackway divided into sections, cross bonding conductors between the tracks, signals indicating the location of the vehicles and the continuity of the track rails, and two sources of signaling current supplying currents of different characteristics to control such signals.

7. In a signaling system of the type described means for generating three currents of different characteristics, conductors for transmitting said currents, motor vehicles actuated by one of said currents, signaling devices indicative of the occupancy of the block sections of the trackway by motor vehicles operated by the second of said currents, and a translating device responsive to the condition of the trackway as regards continuity operated by the third of said currents.

8. In a railway signaling system; a plu-

rality of trackways divided into block sections; means coöperating with the rails to form a track circuit in each block section; translating devices one controlled by each track circuit; signaling devices one controlled by each translating device; conductors connecting one rail of each block section of one trackway with the corresponding rail of the corresponding block section of every other trackway; reactance coils, one connected to each end of the other rail of each of the block sections; conductors, one joining the two coils of every pair of adjacent reactance coils; conductors each connecting together all of the corresponding last mentioned conductors of the several tracks; a car; a source of propulsion current, one terminal of the source being connected through a reactance bond to each rail of each trackway; means connected to the other terminal for conveying current to the car upon its trackway.

9. In an electric railway signaling system, in which the running rails are used as part of the return for the propulsion current, the combination of a supplementary return conductor for the propulsion current, a plurality of track circuits, two or more inductive cross bonds for each track circuit, means for electrically connecting any two adjacent cross bonds to each other, and means for electrically connecting any such pair of cross bonds or any single cross bond to the supplementary return conductor. 75

In testimony whereof, I affix my signature, in the presence of two witnesses.

FITZHUGH TOWNSEND.
